UNITED STATES PATENT OFFICE

2,540,336

ELECTRIC SNAP SWITCH

Albert Käser, Zug, Switzerland, assignor to Landis & Gyr, A. G., Zug, Switzerland, a body corporate of Switzerland

Application February 4, 1948, Serial No. 6,131
In Switzerland April 19, 1939

Section 1, Public Law 690, August 8, 1946
Patent expires April 19, 1959

2 Claims. (Cl. 200—67)

1

The present invention relates to an improved electric switch of the type having a contact member which moves through a relatively short path of travel in actuation of the switch.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations, and improvements herein shown and described.

The accompanying drawings, referred to herein and constituting a part hereof, illustrate one embodiment of the invention, and together with the description, serve to explain the principles of the invention.

The present invention has for its object the provision of an electric switch of the type having a movable contact member which has a relatively short travel in which the contact tilts without the employment of a magnet and the movable system for the contact has but two bearing points. Another object is the provision of such an improved switch in which the movable system bearing the movable contact consists of a single, integral element having a pair of rigidly arranged bearing points.

Of the drawings:

Fig. 1 is a side elevation, certain parts being shown in section, of an illustrative embodiment of the invention; and,

Fig. 2 is a sectional view taken along line II—II of Fig. 1.

In the illustrative embodiment of the invention herein shown and described it is assumed that the switch forms a part of an immersion thermostat, i. e., of an instrument, which controls the supply of energy that serves for the heating of a liquid in a liquid container, such as, for example, a boiler which is employed in hot water installation for use in houses.

Of the immersion part of the thermostat there is indicated a tube 1 and a rod 2, which two parts are made of materials of different coefficients of expansion, so that according to the temperature conditions of the liquid to be heated there results a relative movement between these two parts at the ends thereof shown in the drawing.

On the tube 1 there is fixed, with the interpositioning of an insulating plate 3, a bar or strip 4, which has a lug 5 bent out of the central portion thereof and the free end of which is bent

2

down and is provided with a screw 6 serving for the connection of a conductor. At the other end of the bar or strip 4 there is mounted an angle piece 8 longitudinally adjustable with respect thereto by means of screws 7.

Angle-shaped notches 9 and 10 in the lug 5 and angle piece 8 respectively form bearing points for the movable system of the switch. This movable system itself consists of a leaf shaped tilting element 11—12 of resilient, spring material, which comprises a portion 11 stiffened by means of bent up flanges 13 along longitudinal edges thereof, and a spring tongue 12. This spring tongue is formed as a cut out part of and surrounded by the stiffened portion 11. By means of one end of the stiffened part 11 and the free end of the spring tongue 12, the tilting element is inserted between the bearing points 9—10 by previously stressing the spring tongue.

20 The stiffened part 11 of the tilting element at the part thereof beyond the free end of the spring tongue 12 bears the movable contact member 14 of the switch and this, when the switch is opened, lies against an adjustable abutment 15, which is connected through an insulating block 16 to the bar or strip 4. The contact member 14 lies opposite a fixed contact 17, which is mounted by means of an insulating bush 18 in the bar or strip 4 and to which a second conductor can be connected by means of a nut 19.

25 The rod 2 is formed at its upper end into an eye which surrounds the rod or strip 4 and the stiffened part of the leaf-shaped tilting element 11—12 and by means of an adjustable insulating pin 20 forming the switch actuating means, rests against the part 11 near the bearing point 10. 21 is an abutment, which prevents the pressing through of the tilting element 11—12 up to the dead point.

30 The method of operating of the above described switch is based on the known principle of the toggle joint or reversible triangle of forces. It is to be assumed that on the cooling of the liquid in the boiler below the set temperature the rod 2 falls. In such movement the insulating pin 20 presses on the tilting element 11—12. The latter by reason of its leaf shaped form and material is somewhat resilient notwithstanding the stiffening in the transverse direction, so that when the switch is opened there first takes place a stressing of the stiffened part 11. With further dropping of the rod 2 this stressing of the part 11 increases until its force overcomes the force of the spring tongue 12 and the triangle 35 of forces formed between the bearing points

9—18 and the pressure point of the insulating pin 20 suddenly collapses, i. e., the element 11—12 tilts and the movable contact member 14 comes into engagement with the fixed contact 17.

The abutment 21 preventing the pressing through of the tilting element 11—12 up to the dead point thereof has the result that when the rod 2 by reason of the rising of the temperature in the boiler moves upwards, by the decrease in the pressure exerted by the insulating pin 20, the force of the spring tongue allows the tilting element to spring suddenly back again, whereby the contact member 14 is dragged away from the part 17.

As can be clearly seen from the above description the switch according to the invention is of the greatest possible simplicity, since it has the minimum number of bearing points, which are theoretically necessary for switches having a tilting action, and since the movable system of the switch consists of a single piece, whereby the manufacture and assembly are simplified as compared with the known switches of this kind.

Instead of doing away with the elastic arrangement of the tilting element in operative combination with the insulating pin 20, the latter can be elastically inserted in the eye-shaped part of the rod 2, so that when starting the switching motion this spring is at first stressed or released.

According to the example of construction the switch is assumed to be a single pole on-and-off switch. It can obviously also be made with a plurality of poles. The switch can also be made as a change-over switch, in which case the abutment 21 is dispensed with, the abutment 15 would serve as a fixed contact connected to a further conductor and the controlling pin 20 would lie on the other side of the tilting element 11 opposite to a controlling pin likewise connected to the rod 2. In this case the tilting element would thus tilt over the dead point at each switching motion.

The employment of the invention is in no way confined to an immersion thermostat, since the invention can be employed universally on electric switches where it is desired to keep the travel of the movable contact small. It can also be employed in combination with a switch that remains in the closed position after being switched on and has to be opened by hand. The fundamental arrangement of the parts of the switch proper can then be the same as in the example of construction, only instead of the abutment 21 a lever or the like must be provided, which, when actuated by hand, permits the return of the tilting element over the dead point.

The invention in its broader aspects is not limited to the specific mechanisms shown and described but departures may be made therefrom, within the scope of the accompanying claims, without departing from the principles of the invention and without sacrificing its chief advantages.

What is claimed is:

1. An electric switch comprising, in combination, a longitudinally extending strip element made of resilient material stiffened along the length thereof, a movable contact carried adjacent one end of said element, said element being formed with an integral, spring tongue portion having a free end toward said contact and intermediate the ends of said element, and a pair of fixed, opposed bearing points loosely engaging said free end of said tongue portion and the end of said element opposite said contact said element being in a condition of stress between said points.

2. An electric switch comprising, in combination, a longitudinally extending resilient strip element having stiffened longitudinal edges extending substantially the entire length of said element, a movable contact carried adjacent one end of said element, said element being formed with an integral, cut-out spring tongue portion having a free end toward said contact and intermediate the ends of said element, and a pair of fixed, opposed bearing points loosely engaging said free end of said tongue portion and the end of said element opposite said contact said element being in a condition of stress between said points.
